UNITED STATES PATENT OFFICE

152,006

DESIGN FOR A FLOOR RENOVATOR

Howard C. Lilly, Sharon, Mass., assignor to
Masury-Young Company, Charlestown, Mass.,
a corporation of Massachusetts

Application August 6, 1947, Serial No. 140,734

Term of patent 3½ years

(Cl. D9—2)

To all whom it may concern:

Be it known that I, Howard C. Lilly, a citizen of the United States, residing at Sharon, in the county of Norfolk and State of Massachusetts, have invented a new, original, and ornamental Design for Floor Renovator, of which the following is a specification, reference being had to the accompanying drawing, forming part thereof.

Figure 1 is a plan view of a floor renovator, showing my new design,

Figure 2 is a side elevation, and

Figure 3 is a front elevation.

I claim:

The ornamental design for a floor renovator, substantially as shown.

HOWARD C. LILLY.
